US0D1024932S

(12) **United States Design Patent** (10) **Patent No.:** **US D1,024,932 S**
(45) **Date of Patent:** **** Apr. 30, 2024**

(54) **CONNECTOR PLUG**

(71) Applicant: **WALSIN LIHWA CORPORATION**,
Taipei (TW)

(72) Inventors: **Ko-Ming Chen**, Taipei (TW);
Shih-Hsiang Wang, Taipei (TW);
An-Hung Lin, Taipei (TW);
Min-Chuan Wu, Taipei (TW);
Shao-Pei Lin, Taipei (TW);
Chien-Chung Ni, Taipei (TW);
Chun-Ying Lin, Taipei (TW)

(73) Assignee: **WALSIN LIHWA CORPORATION**,
Taipei (TW)

(**) Term: **15 Years**

(21) Appl. No.: **29/830,113**

(22) Filed: **Mar. 10, 2022**

(30) **Foreign Application Priority Data**

Dec. 24, 2021 (TW) 110307067

(51) **LOC (14) Cl.** **13-02**

(52) **U.S. Cl.**

(57) **CLAIM**

The ornamental design for a connector plug, as shown and described.

DESCRIPTION

FIG. 1 is a top perspective view of a connector plug showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom perspective view thereof.

The broken lines depict portions of the connector plug that form no part of the claimed design.

1 Claim, 8 Drawing Sheets
